M. A. SMITH,
FIRE POLISHING APPARATUS,
APPLICATION FILED AUG. 17, 1916. RENEWED JUNE 17, 1918.
1,274,095. Patented July 30, 1918.

UNITED STATES PATENT OFFICE.

MAURICE A. SMITH, OF JEANNETTE, PENNSYLVANIA.

FIRE-POLISHING APPARATUS.

1,274,095.

Specification of Letters Patent. Patented July 30, 1918.

Application filed August 17, 1916, Serial No. 115,413. Renewed June 17, 1918. Serial No. 240,523.

To all whom it may concern:

Be it known that I, MAURICE A. SMITH, a citizen of the United States, and resident of Jeannette, in the county of Westmoreland and State of Pennsylvania, have invented a new and useful Improvement in Fire-Polishing Apparatus; and I do hereby declare the following to be a full, clear, and exact description thereof.

10 My invention relates to fire-polishing apparatus.

My invention relates more particularly to that type of fire-polishing apparatus in which air and gas are delivered to a burner, 15 the combustion chamber being so shaped as to direct the flame downwardly so as to fire-polish the interior or exterior of an article on the principle of the Owens Patent No. 628,027, July 4, 1899, whereby a pressed cutting 20 glass blank is fire-polished upon the interior to remove any defects or imperfections caused by the action of the plunger in pressing the glass in the mold.

The object of my invention is to provide 25 a simple form of apparatus by which the article to be polished is quickly brought into position for polishing, and withdrawn therefrom and lifted from the support which holds it during the polishing operation, so 30 that it may be conveniently removed therefrom.

In the accompanying drawing, Figure 1 is a plan view of my improved apparatus; Fig. 2 is a longitudinal section; Fig. 3 is a 35 view of a portion of the apparatus where the article is supported in position to be polished on the exterior.

Referring to the drawing, the numeral 2 designates a suitable table or platform 40 mounted on a frame 3, which in turn is preferably mounted on wheels 4 for convenience in transporting the device from one part of the factory to another.

A burner 5 of well-known construction is 45 supported on the adjustable bracket 6 carried by the table 2. This bracket is secured to the slideable member 7 which telescopes with and is adapted to move up and down on the post 8. The adjusting screw 9 is 50 adapted to raise and lower the member 7 to bring the burner to the desired height according to the article to be operated on.

Air is supplied from the tank 10 located 55 below the table in the frame 3, said air being conducted by the pipe 11 to the burner where it is mixed with the gas introduced

by the pipe 12. The construction of the burner 5 is such that the air and gas when ignited in the combustion chamber, form a hot flame which is directed downwardly and 60 confined within a comparatively small area.

Resting upon the table 2 are the formers 13 and 14, the former 13 being concave in form to receive a correspondingly shaped article and the former 14 is convex so as to receive the article when inverted for the purpose fully hereinafter set forth.

The formers 13 and 14 have each a valve or movable central portion 15 which are adapted to be brought into register with the 70 lifting rods 16 and 17. These rods are supported in the frame below the table, and are operated by the handles 18 pivoted at 19 and connected to said rods by the links 20. The upper ends of the rods extend through openings 21 in the table and said rods are provided with the collars 22 which rest on the shoulders 23 formed in the table. A projection 24 on the upper end of the rod enters a recess 25 formed in the valve 15 when the 80 rod and said valve are brought into register with each other.

The formers 13 and 14 are provided with suitable handles 26 for moving said formers on the table.

The article to be fire-polished, which for illustration may be the bowl 27, after having been pressed and removed from the mold, is moved along the table in position to bring it under the burner 5. The hot 90 blast is directed from the burner onto the interior of the bowl, while supported in the former and the fire-polishing action takes place. When this is completed, the operator moves the former 13 back along the table 95 until the valve 15 is brought into register with the lifting rod 16 whereupon the operator moves the lever 18 to lift the rod 16, and the upper end of said rod engaging said valve is lifted together with the bowl supported thereon to the position indicated in dotted lines Fig. 2. In this manner the bowl is quickly removed from the former and elevated in position for lifting and transferring to the former 14, where the 100 exterior of the article is to be fire-polished, the bowl being inverted and supported on the frame 14 in the manner indicated in full lines Fig. 3. The former 14 is then moved over into position to be subjected to the 110 action of hot blast, and is then withdrawn and brought into register with the rod 17.

whereupon by operating the lever 18 the bowl is lifted by the rod to the position indicated by dotted lines Fig. 3 to be removed therefrom and taken to the leer.

5 By my invention, while one bowl is being fire-polished the other is being removed from the former, and in this way one operator can manage two formers. All he has to do is to move the former under the blast, 10 withdraw it therefrom, and by operating the lifting lever, the article is lifted from the former in convenient position to be taken away.

The movable valve or section 15 not only 15 provides for the lifting of the articles from the former, but at the same time opens up a passageway for the circulation of air through the former, thereby cooling the same and preventing its overheating.

20 What I claim is:

1. In fire-polishing apparatus, the combination of a suitable frame, a table, a hot blast device supported above said table, a former carried by said table and movable thereon, a movable central portion in said former, and lifting means detached from and adapted to register with said movable portion.

2. In fire-polishing apparatus, the combination of a suitable frame, a table, a hot blast device supported above said table, a 25

former carried by said table and movable thereon, a movable central portion in said former, a lifting rod detached from and adapted to register with said movable portion, and means for raising said rod. 35

3. In fire-polishing apparatus, the combination of a suitable frame, a table, a hot blast device supported above said table, a former carried by said table and movable 40 thereon, a movable central portion in said former, a lifting rod passing up through an opening in said table detached from and adapted to register with said movable portion, and means for lifting said rod. 45

4. In a fire-polishing apparatus, the combination of a suitable frame, a table, a hot blast device supported above said table, a former carried by said table and movable thereon, a movable central portion in said former, a lifting rod extending up through an opening in said table and normally below the level of said table, said rod being detached from and adapted to register with 50 said movable portion, and means for lifting 55 said rod.

In testimony whereof I, the said MAURICE A. SMITH, have hereunto set my hand.

MAURICE A. SMITH.

Witnesses:

I. BEULCKE,
E. B. STERN.
